(57) **CLAIM**

An ornamental design for a scissors, as shown.

DESCRIPTION

FIG. 1 is a perspective view of a scissors showing our new design;

FIG. 2 is a left elevational view thereof;

FIG. 3 is a right elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken line showing is for illustrative purposes only and forms no part of the claimed design.
